UNITED STATES PATENT OFFICE.

JOSEPH LACHANCE, OF LOS ANGELES, CALIFORNIA.

WAVE-MOTOR.

1,207,939.

Specification of Letters Patent. Patented Dec. 12, 1916.

Application filed January 31, 1916. Serial No. 75,424.

To all whom it may concern:

Be it known that I, JOSEPH LACHANCE, a citizen of the United States, residing at Los Angeles, county of Los Angeles, and State 5 of California, have invented certain new and useful Improvements in Wave-Motors, of which the following is a specification.

My invention relates to motors and particularly to wave operated motors.

10 The object of my invention is to provide a motor for transmitting the energy from a wave actuated member to the work at a uniform rate or power.

15 A further object of my invention is to provide a device of the class mentioned whereby the power shaft may be actuated by any desired number of wave actuated members or prime movers.

20 A further object of my invention is to provide, in a device of the class mentioned, improved means for regulating the speed of the power shaft.

Other objects will appear hereinafter.

With these objects in view my invention 25 consists generally in providing a suspended weight which is raised by the reciprocation of a wave actuated vane and in providing suitable mechanism between said weight and a power shaft for driving the latter through 30 the medium of the downward action of the weight.

My invention further consists in a device as mentioned further characterized by interposing a ratchet mechanism in the connection 35 between the weight and the power shaft whereby the latter is driven in one direction only upon the reciprocation of the weight.

40 My invention further consists in a wave motor as mentioned further characterized by a governor comprising a stationary member and a rotary member operatively connected to the power shaft, a brake shoe carried by the rotary member, a cam for actuating said 45 shoe and a wing connected to said cam for operating the same.

My invention further consists in various 50 details of construction and arrangements of parts, all as will be fully described herein- after and particularly pointed out in the claims.

55 My invention will be more readily understood by reference to the accompanying drawings, forming a part of this specification and in which—

Figure 1 is a diagrammatic side elevation illustrating my improved motor, Fig. 2 is a diagrammatic end view of the same, Fig. 3 is a detail sectional view of the speed regulator taken on substantially the line $x-x$ 60 of Fig. 4, and Fig. 4 is a transverse section of the same taken on substantially the line $y-y$ of Fig. 3.

Referring now to the drawings, 1—1 indicate wave actuated vanes pivotally supported as at 2 upon suitable foundations or supports provided for the same. These vanes may be of any desired form but preferably similar to those described in my Patent No. 1,154,033, issued September 21, 1915. These vanes are each provided with cables 3 to limit their forward or return movement. Secured to the vanes are power cables 4 which extend downwardly under idlers 5 and thence to the motor forming the 75 subject matter of the present invention.

The cables 4 extend under idlers 6 and thence upwardly and over pulleys 7 and upon the depending ends of the cables 4 are secured weights 8—8. It should be understood that there are as many cables 4 and weights 8 as there are vanes 1 and that the number is dependent upon the power it is desired to produce.

Arranged adjacent each of the weights 8 85 is a vertically disposed endless cable 9 passing over an upper pulley 10 and a lower pulley 11 and the weight 8 is secured fixed upon said cable as shown clearly in Fig. 1. In order that the pulley 10 shall be positively driven by the cable I prefer to arrange several bights of the cable about the pulley as indicated in Fig. 2. It is obvious that with the reciprocation of the vane 1, by the action of the waves, the weight 8 90 will be raised and upon return of the vane to normal or vertical position the weight will drop thereby rotating the pulley 10 through the medium of the cable 9. In order that the shaft 12 upon which the pulley 10 is mounted shall be driven in one direction only, a suitable ratchet connection 13 is provided between said pulley and shaft.

Fixed upon the shaft 12 is a sprocket 105 gear 14 which is connected by a sprocket chain 15 to a sprocket gear 16 on a shaft 15'. Fixed to the shaft 15' is a gear 17 meshing with a gear 18 on a power shaft 19, and the latter is equipped with a belt wheel 110

20 or equivalent device from which the power may be transmitted to the work.

It is obvious that with the mechanism above described, the power shaft will be 5 driven uniformly in one direction and in order that, with the reciprocation of the weights 8, the power shall be substantially uniform, I prefer to employ a number of vanes and coöperating weights and cables, 10 although in the drawings I have illustrated but two, it being clearly understood that any number may be employed without departing from the spirit of my invention or the showing made in the drawings.

15 In order to govern the speed of the motor I provide a novel regulator. 21 indicates a fixed or nonrotary shaft to which is rigidly secured a disk 22. 23 indicates a shaft in axial alinement with the shaft 21 and to 20 which is secured a pinion 24 meshing with a gear 25 fixed to the shaft 15'. A cage 26 is fixed to the end of the shaft 23 and incloses the disk 22. Arranged within the 25 cage 26 between suitable guides are brake shoes or blocks 27. Although any suitable means may be employed for guiding the brake shoes and maintaining them in position, I have illustrated the walls of the cage 26 as provided with ribs or bosses 28. Adjacent each of the blocks 27 is a cam disk 29 mounted upon pintles 30. Each of the cam disks is provided with a radially extending arm 31 upon which is mounted a wing 32 which forms a resistance element by engaging 35 the atmosphere. It is obvious that with the rotation of the device, the wings, through the resistance of the air, will cause the cam disks to actuate the brake shoes and that as the speed increases the shoes will be 40 pressed with greater force upon the periphery of the disk 22. In order to regulate the device to the desired speed the wings 32 are adjustably mounted on the arms 31, it being obvious that the farther the wings are ar- 45 ranged from the center of rotation the quicker the brakes will act and therefore the slower the device will operate. The operation of the device is clear from the above de- scription.

50 I claim:—

1. In a wave motor, a weight, a wave actuated vane, an endless cable having said weight secured thereto, means connecting said vane and said weight for raising the latter upon oscillation of the former, a pulley and pulley shaft, a ratchet connection between said pulley and said shaft for operating said shaft upon the fall of said weight, a power shaft and an operative connection

between said pulley shaft and said power 60 shaft, substantially as described.

2. In a wave motor, a pair of super-imposed pulleys, an endless cable passing over said pulleys, a weight fixed to said cable, a pulley shaft, a ratchet connection between 65 said pulley shaft and the respective pulley, a wave actuated vane, means connecting said vane and said weight for raising the latter with the reciprocation of the former, a power shaft and an operative connection be- 70 tween said pulley shaft and said power shaft, substantially as described.

3. In a wave motor, a pulley shaft, a plurality of pulleys on said shaft, a ratchet connection between each of said pulleys and 75 said shaft, a corresponding number of endless cables passing over said pulleys respectively, a weight on each of said cables, a like number of wave actuated vanes, cables connecting said vanes with said weights re- 80 spectively for raising the latter upon reciprocation of the former, a power shaft and an operative connection between said pulley shaft and said power shaft, substantially as described.

4. In a wave motor, a power shaft, a reciprocating wave actuated vane, driving mechanism connecting said vane and said shaft, in combination with a governor for 90 said shaft comprising a fixed disk, a rotary member adjacent said disk, a connection be- 95 tween said power shaft and said rotary member, a brake shoe carried by said rotary member and engaging the periphery of said disk, a cam for actuating said shoe, an arm on said cam and a wing on said arm, sub- stantially as described.

5. In a wave motor, a power shaft, a reciprocating wave actuated vane, driving mechanism connecting said vane and said 100 shaft, in combination with a governor for said shaft comprising a fixed disk, a rotary member adjacent said disk, a connection be- 105 tween said power shaft and said rotary member, a brake shoe carried by said rotary member and engaging the periphery of said disk, a cam for actuating said shoe, a radial arm on said cam and a wing adjustably mounted on said arm, substantially as de- 110 scribed.

In testimony whereof I have signed my name to this specification in the presence of two subscribing witnesses.

JOSEPH LACHANCE.
